(57) CLAIM

The ornamental design for a bottle, as shown and described.

DESCRIPTION

FIG. 1 is a top, front, left perspective view of a bottle showing a new design;

FIG. 2 is a front elevational view thereof which is identical to a rear elevational view thereof;

FIG. 3 is a left side elevational view thereof which is identical to a right side elevational view thereof;

FIG. 4 is a top plan view thereof; and,

FIG. 5 is a bottom plan view thereof.

The broken lines illustrate portions of the bottle that form no part of the claimed design.

1 Claim, 4 Drawing Sheets
